UNITED STATES PATENT OFFICE.

PAUL J. REES, OF MEADVILLE, PENNSYLVANIA.

TABLE-SWEEPER.

1,115,023.

Specification of Letters Patent.

Patented Oct. 27, 1914.

Application filed June 1, 1914. Serial No. 842,260.

To all whom it may concern:

Be it known that I, PAUL J. REES, a citizen of the United States, residing at Meadville, in the county of Crawford, State of Pennsylvania, have invented certain new and useful Improvements in Table-Sweepers; and I do hereby declare the following to be a full, clear, and exact description of the invention, such as will enable others skilled in the art to which it appertains to make and use the same.

This invention relates to a household device, and especially to a novel device adapted for use upon a dining or other table.

15 The object of the invention is to provide a novel device by means of which crumbs or other fragments may be expeditiously and effectually removed from the table without danger of brushing them onto the floor.

20 An important object is to provide a device for this purpose which when passed over the top of the table will brush the fragments of food, such as crumbs into a receptacle contained within the body of the device itself.

25 Another object is to provide a device of this character which will be effective in service, and comparatively inexpensive in manufacture.

30 With these and other objects and advantages in view, my invention consists in the novel construction, arrangement and combination of parts as will be hereinafter fully described, and illustrated in the accompanying drawings in which.

Figure 1 is a perspective view of my improved device, Fig. 2 is a bottom plan view thereof, Fig. 3 is a cross sectional view on the line 3—3 of Fig. 2, and Fig. 4 is a cross 40 sectional view on the line 4—4 of Fig. 2.

Referring more particularly to the drawings, the numeral 5 designates the outer casing of my device, which comprises a top wall 6 bent to form side walls 7, and further comprises end walls 8. A handle 9 of any desired shape is secured upon the top wall 6 for the purpose of providing hand engaging means whereby the device may be readily moved on the table.

50 Secured within the casing 5 adjacent each end thereof are supporting frames 10, each of which comprises a rectangular body secured to the outer casing 5 at its side walls 7 by means of bolts 11. Within each of the 55 frames 10 are mounted, as at 12 a pair of

rollers 13 preferably rubber tired for a purpose to be described.

The numeral 14 indicates the brush, as a whole, which comprises a central spindle 15. At its ends the spindle 15 is provided with 60 rollers 16 adapted to be disposed in engagement with the rollers 13 within the frames 10. In order that the brush 14 may be readily removed from or engaged with the frames 10, I preferably 65 provide the inner sides 17 of the frames 10 with slots 18, the curved inner ends of which form one-half the bearings for the spindle 15. After the brush 14 is placed in position with the ends of the spindle 15 disposed 70 within the slots 18, it is prevented from displacement by means of bars 19 pivoted as at 20 upon the inner faces of the frames 10, and provided with curved recesses 21 adapted 75 to coöperate with the slots 18 for forming complete bearings for the spindle 15. The bars 19 are formed preferably of spring metal and carry at their free ends projections 22 adapted to be engaged within openings in the inner walls of the frames 10, 80 whereby swinging of the bars 19 is prevented.

From the foregoing it will be obvious that when the device is pushed along the top of the table the rollers 13 will rotate, thereby 85 rotating the brush 14. It will be apparent that as the device is pushed along the table, the crumbs or other fragments will be swept along by the brush 14. In order to catch and retain the crumbs or other matter, I 90 provide a pair of pans, designated as a whole by the numeral 24 which are pivoted within the casing 5 between the frames 10, at their lower outermost edges by longitudinally extending wires 25. It will thus be 95 seen that the pans 24 may be swung upon the wires 25 as pivots. Each of the pans 24 comprises a back wall 26, a bottom 27, ends 28, and an angular front portion 29 which is disposed close to the brush 14. The pans 24 100 are held in their normally horizontal or uppermost position by means of springs 30 which have their body portions disposed above the brush 14 and their ends connected with the upper edges of the ends 28, whereby the pans 24 may be swung upwardly to their normal positions with their ends 28 engaging the frames 10.

As the brush 14 is rotated as previously described, the crumbs and other fragments 110

will be swept into the pans 24, their passage thereinto being facilitated by the outer inclined walls 29 of the pans. When the pans become too full, they may be readily emptied by swinging them downwardly upon the wires 25 as pivots, whereupon the passage of the crumbs therefrom is facilitated by the provision of an inner inclined plate 31 adjacent to and inclined in an opposite 10 direction from the plate 29.

By the structure disclosed, it will be apparent that by swinging the bars 19 so as to disengage the projections 22 from the openings 23, the brush 14 may be bodily removed 15 from the device for cleansing.

It will be readily understood that I reserve the right to make such changes in the form, construction and arrangement of parts as will not depart from the spirit of the invention, nor the scope of the subjoined 20 claims.

Having thus described my invention, I claim:

1. A table sweeper comprising a casing, 25 frames secured therein adjacent its ends, a pair of rollers journaled within each of said

frames, said frames being provided with upwardly extending slots, a brush having its journals mounted in said slots, bars pivoted on said frames and provided upon 30 their edges with recesses for engagement with said journals, and means for detachably securing the free ends of said bars upon said frames.

2. A table sweeper comprising a casing, 35 rectangular open frames secured therein adjacent its ends, a pair of rollers journaled within each of said frames, said frames being provided with upwardly extending slots, a brush having its journals mounted in said 40 slots, bars pivoted on said frames and provided upon their edges with recesses for engagement with said journals, and projections on said bars adapted to engage within openings formed in said frames. 45

In testimony whereof, I affix my signature, in the presence of two witnesses.

PAUL J. REES.

Witnesses:

F. J. DAILEY,
GEO. W. ARMSTRONG.
